RAY P. JACKSON, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

PROTECTIVE MEANS FOR AN ELECTRICAL DISTRIBUTING SYSTEM.

1,224,172.

Specification of Letters Patent.

Patented May 1, 1917.

Application filed July 14, 1915. Serial No. 33,777.

To all whom it may concern:

Be it known that I, RAY P. JACKSON, a citizen of the United States, and a resident of Edgewood Park, in the county of Allegheny and State of Pennsylvania, have invented a new and useful Improvement in Protective Means for an Electrical Distributing System, of which the following is a specification.

10 My invention relates to electrical systems of distribution, and it has special reference to distributing circuits which supply power to a plurality of translating devices, such as incandescent lamps and the like, that are connected, either singly or in groups, in series relationship with one another and disposed at isolated points in the circuits.

20 More particularly, my invention refers to protective devices that are adapted to be inserted in circuits of the above-indicated character in order to insure continuity of service and afford protection to the series transformers which are employed in combination with the translating devices.

25 In alternating-current lighting systems employing incandescent lamps connected directly in circuit and in series relationship with one another, it is usual to provide means for closing the circuit whenever the 30 filament of an isolated incandescent lamp breaks. Such protective devices usually consist of automatic circuit closers which, when subjected to the full line potential momentarilly impressed thereupon as a result of the interruption of the main circuit, reclose the main circuit, thereby reestablishing normal service conditions. However, such automatic circuit closers are used in conjunction with incandescent lamps only

40 and, to my knowledge, have never been employed as protective devices for transformers which are connected in series relationship with one another in a distributing circuit. Again, automatic circuit closers heretofore employed have not been of such construction as to permit them to be repeatedly used for similar service, but it has been necessary to replace such devices, either wholly or in part, before they may be restored to their initial condition.

45 In distributing circuits of the character

now in common use, protective means for series transformers are essential in order to preclude dangerous potential stresses from being impressed upon the transformer windings when the circuits comprising the secondary windings of such transformers are interrupted by reason of the breaking or the burning out of the filaments of the incandescent lamps which are connected in circuit therewith. Moreover, it is desired that such protective means be simple in construction, requiring only a small expenditure of labor and time in restoring normal conditions in the circuit, while, at the same time, the protective devices are entirely effective for suppressing subsequent disturbances arising from further burnouts or breaks in the lamp filaments.

50 My invention is designed for the accomplishment of these objects and other objects to be hereinafter disclosed.

Figure 1 is a diagrammatic view of an alternating-current lighting circuit embodying a form of my invention; Fig. 2 is a plan view of a protective device embodying a preferred form of my invention, and Fig. 3 is a side view, partially in section, of the device shown in Fig. 2.

55 Referring to Fig. 1, an alternating-current series circuit 1 is supplied with power from any suitable source (not shown) through the mains 2. At isolated points in the circuit 1, series transformers 3 are disposed, the primary windings 4 thereof being connected in series-circuit relationship with the main circuit, substantially as shown. Secondary windings 5 of the transformers 3 constitute local circuits, each comprising a plurality of translating devices or incandescent lamps 6 which are, in turn, connected in series relationship with one another and with the secondary windings 5. The circuit 1, it is apparent, is commonly used in lighting systems embodying low-voltage tungsten lamps which may be substituted for arc lamps heretofore extensively employed in series lighting systems. Of course, it will be understood that each of the local circuits 7, comprising the secondary 60 windings 5 and the translating devices 6, may furnish power to a single incandescent

lamp only or to a plurality of them, as described.

Inasmuch as the filaments of the lamps 6 are liable to burn out or be broken, thereby 5 interrupting the circuits through the secondary windings 5, it is important that protective means be provided for automatically and permanently short-circuiting the secondary windings 5 when such interruptions 10 occur. To this end, I provide protective devices 8 which comprise spaced spark-gap members 9 mounted upon an insulating base 10. The spark gap members 9 are adjustable thereby permitting the break-down 15 strength of the resulting spark gaps to be regulated to the desired or predetermined voltages. It is well known that, when the circuit through the secondary winding of a series transformer is interrupted, the 20 common magnetizable iron core member becomes magnetically saturated to a very high degree, by reason of the high current flowing through the primary winding thereof which, on this occasion, is equivalent to a 25 high exciting current. The high magnetic saturation of the magnetic cores of series transformers, such as core members 11 of the transformers 3, induces very high and dangerous electromotive forces in the sec- 30 ondary windings 5, thereby subjecting the insulation of the windings to high-voltage stresses which are of such character as to substantially preclude uninterrupted service. In order to prevent the trans- 35 formers 3 from burning out when such abnormal conditions obtain, the protective devices 8 are so adjusted that the spark gaps between the spaced terminals 9 will break down at less than the dangerous value 40 of the abnormal voltages. For instance, the sparks gaps should be so adjusted as to break down at values less than 100% over-voltage. If a protective device 8 is designed to continuously withstand 350 volts, which 45 is common practice, it should be so adjusted as to break down and afford a permanent short circuit to its associated secondary winding 5 when 700 volts are impressed thereupon.

50 In Figs. 2 and 3, a preferred form of my protective device 8 is illustrated. The spark-gap members 9 constitute threaded members or screws which are provided with adjusting heads 12. The shank portions of 55 the screws 9 extend through terminal blocks 13 which are secured to the insulating base 10. By means of terminals 14, electrical connections are made to the protective device. The shanks of the screw members 9 60 are provided with longitudinally extending openings 15, the members 9 being so disposed that the openings 15 are adjacent to, and in axial alignment with, each other. In each of the openings 15, I place a body of 65 plastic metal of low fusibility such, for ex-

ample, as a lead fuse wire. The openings 15 may be so drilled that standard fuse wire will snugly fit therein. The spark gap between the coöperative electrodes 9 may then be adjusted by any suitable gage, such as a 75 copper plate. When the circuit comprising the secondary winding 5 is interrupted, the high electromotive force induced therein will effect a spark discharge between the electrodes 9 and the exposed surfaces of the metallic bodies 16 will constitute the arcing surfaces for sustaining these sparks. As a result, the arcs will cause the lead bodies 16 to melt and, as they flow from the openings 15, will unite to form a continuous electric path, thereby automatically and permanently short-circuiting the secondary winding 5. It will be noted that, when arc discharges of the above-mentioned character occur, the fusible bodies 16 contained in the 80 openings 15 will melt together to form a homogeneous mass instead of burning back and increasing the length of the spark gap. This is an important feature since it insures maximum protection for the transformers. 85 90

After the burned-out incandescent lamp has been replaced and the secondary circuit put into operative condition, the spark gap may be reset at the expenditure of only a small amount of labor and time. To illustrate, the electrodes 9 are unscrewed sufficiently to cause the union therebetween to break. The gage is then interposed between the arcing surfaces of the electrodes 9, and the electrodes are subsequently tightened to closely engage the spark gap gage. As a result, the bodies of metal 16 are smoothed off at the arcing surfaces and forced back into the openings 15, thereby restoring the protective device 8 to its initial 95 state.

While I have shown and described, in detail, one embodiment of my invention, it will be apparent that many modifications may be made therein without departing from the spirit and scope of the appended 110 claims.

I claim as my invention:

1. A protective device comprising adjustable spaced spark-gap members composed of 115 material of high fusibility and provided with longitudinally extending openings, and bodies of metal of low fusibility disposed in said openings in the spark-gap members.

2. A protective device comprising a pair of similar and spaced spark-gap members composed of material of high fusibility and provided with longitudinally extending openings, and bodies of plastic metal of low fusibility disposed in said openings in order to constitute the arcing surfaces for said spark-gap members.

3. A protective device comprising adjustable spaced spark-gap members severally 120

provided with a longitudinal opening that is alined with a corresponding opening in the other member, and bodies of metal of low fusibility disposed in said openings.

5 4. A protective device comprising adjustable spaced spark-gap members that are recessed at their arcing ends, and bodies of

metal of low fusibility disposed in said recessed ends.

In testimony whereof, I have hereunto 10
subscribed my name this 30th day of June,
1915.

RAY P. JACKSON.
